UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

STEAM BOILER

Application filed May 21, 1924. Serial No. 714,787.

My present invention relates to steam boilers of a type particularly adapted for very high pressures. In order to provide for extremely high pressures, it is desirable to avoid the large drums such as are ordinarily used in steam generators of large capacity, and to this end I have provided, in the illustrative embodiment of my invention, a boiler in which the usual steam and water drum has been eliminated and the necessary reserve water capacity ordinarily obtained by the use of such relatively large diameter drums, is obtained by other means.

My invention will be best understood from the following description and the annexed drawings, in which Fig. 1 is a vertical longitudinal section of a boiler embodying my invention; Fig. 2 is a view from the right of Fig. 1, with some of the parts broken away; Fig. 3 is a perspective of a detail; Fig. 4 is a front view of a portion of one of the headers, with part of the tubes broken away; Fig. 5 is a section on the line 5—5 of Fig. 1, but on an enlarged scale, and Fig. 6 is a view similar to Fig. 1 showing a modification.

Like reference characters indicate like parts in the several views.

In the illustrative embodiment shown in Figs. 1 and 2, the upper portion of a furnace chamber 10, supplied with hot gases from any desired kind of fuel, has positioned over it a steam boiler of the horizontally inclined water tube type, in which a lower bank of tubes 11 is first contacted for substantially its entire length by the upwardly moving furnace gases, these gases then passing over a primary superheater 12 and a secondary superheater or reheat 13, thence over the left-hand end of an upper bank of water tubes 14, and from thence around the upper end of a baffle 15 and down across the tubes 14, to a gas outlet 16, passing between nipples connecting the downtake headers, as will be more fully described hereinafter, the gases then passing downward over the tubes of an economizer 17.

In the illustrative embodiment, the uptake water chamber is made up of a plurality of headers 18 and 19, nippled together at 20, these headers preferably having a curved

cross-section to give them the necessary strength and, in the preferred form, being flattened on one side, as shown best in Fig. 5, to permit the insertion of the tubes in the manner illustrated in that figure, the tubes in each bank being divided across the boiler into groups of three tubes each, with their ends entering into the headers 19 in the manner shown in Fig. 5, so that the tubes of each row will be staggered relatively to the tubes in the rows above and below it, and so that, while the headers 19 will be spaced apart a sufficient distance to permit a tube to be withdrawn between each pair of headers, nevertheless the tubes in each row may be uniformly spaced across the boiler. Each header will be provided with the usual handholes and handhole fittings to give cleaning access to the tubes.

The downtake headers are similar to the uptake headers just described and comprise, in the illustrative embodiment, a set of headers 21 and another set 22 connected by long nipples 23 spaced apart to permit the gases to flow between them to the gas outlet 16.

The primary superheater 12 and the secondary superheater or reheat 13 are provided with tubular headers, in the illustrative embodiment, and U-tubes, the headers being connected by baffling 120, which, with the superheater headers and the connected fins formed thereon as shown, form a baffle to direct the gases across the superheater tubes to the first pass across the upper bank of water tubes 14. The superheater tubes are supported on walls 24, 25 which serve to direct the gases more efficiently across the superheater tubes, these walls resting on the upper row of tubes of the bank 11. Preferably, in order to permit the weight of the superheater tubes to be distributed over a considerable number of rows of tubes, I provide distance pieces 26, 26 beneath each of the walls 24 and 25 to tie several of the uppermost rows of the lower bank of tubes together.

In the illustrative embodiment, the headers 19 and 22 are carried up above the uppermost row of tubes of the bank 14 to a relatively considerable distance, the upper ends 100

of these headers being connected by a row of water tubes 27 on which rests a roof baffle 28, this roof baffle being spaced from the top row of tubes 14 a sufficient distance to permit an easy turn for the gases passing over the top of the baffle 15.

Each of the headers 19 and 22 is provided with an extension piece or pipe extending for a considerable distance above the roof baffle 28, the extension pieces 29 each being nipped at 30 to an uptake header 19 and each of the downtake extensions 31 being nipped at 32 to a downtake header 22. Preferably, these extensions 29 and 31 are circular in cross-section and of substantially the same area as the headers 19 and 22.

In the illustrative embodiment, a horizontal box 33 extends across the tops of the extensions 31, being nipped to each of such extensions at 34. A row of steam circulating tubes 35 extends from each uptake extension 29 to the horizontal box 33.

In the illustrative embodiment, a tube 33^a extends across the boiler and above the box 33, being nipped thereto by nipples 36^a. From the tube 33^a extend steam collector tubes 36, with their upper ends all directed toward and connected to a vertically disposed steam collecting chamber 37, from which leads a main steam pipe 38 to the intake header of the primary superheater 12.

The tube 33^a and the box 33 serve to equalize the steam pressure from side to side of the boiler, thereby preventing an undue difference in the water level in different parts of the boiler. The box 33 and the tube 33^a are so arranged that there is no longitudinal flow of the steam through them other than that necessary to effect the equalization. This is accomplished by making the nipples 36^a come within the limits of a group of the horizontal circulating tubes 35 and opposite the inlet ends of the collector tubes 36. In the illustrated embodiment, I have shown a group of three circulating tubes 35 connecting each header 29 to the box 33. This makes it possible for the steam discharged from the top of each uptake water chamber 19 to flow directly to the steam collecting chamber 37 when steam is generated uniformly from side to side of the boiler.

In case steam is not generated uniformly from side to side, the cross box 33 and the equalizing tube 33^a allow some of the steam to flow from one point to the other along the width of the boiler so as to equalize the pressure between the different parts of the boiler and prevent an undue difference of water level in the different parts of the boiler.

In some cases, the box 33 may be omitted, in which case, the nipples 36^a would connect directly into each section of the downtake water chamber, instead of indirectly through the box 33, as illustrated.

The tube 33^a may be drained by tubes 43

leading to the water storage tubes 41, hereinafter referred to.

Feed water is supplied, in the illustrative embodiment, through a horizontal header 39 to nipples 40, which, in turn, are connected to the downtake extensions 31.

It will be noted that in the boiler as thus described, the steam generated will be carried up through the uptake headers and their extensions and across the boiler through the steam circulators 35 to the cross box 33, from which the steam will flow into the tube 33^a from which it will be collected by the auxiliary pipes 36, which will lead it to the chamber 37 and the main steam pipe.

Since the usual steam and water drum is omitted in the construction described, it is necessary to provide a reserve water capacity. It will also be desirable to arrange the boiler so that the separation of steam and water may occur as completely as possible before the tubes 35 are reached.

To this end, I provide one or more rows of water storage tubes 41 of large section extending between the uptake and downtake water chambers and preferably above the roof baffle 28, these tubes being nipped, in the illustrative embodiment, at either end to the extensions 29 and 31, respectively. Preferably, I also provide a plurality of curved connectors 42 entering the side of the tube 41 and the corresponding extension 29 for the purpose of permitting water that may rise some distance in the extensions 29 to flow downwardly through the connectors 42 to the tubes 41.

If desired, drainage tubes 43 may be provided between the circulators 35 and the tubes 41.

With the arrangement just described, the mixture of steam and water passing up the uptake headers 19 and into the extensions 29 will have the steam largely separated from the water in these extensions, so that the water will flow back through the tubes 41 to the downtake extensions 31, this flow being facilitated by the additional connections formed by the curved connectors 42. Consequently very little water will enter the tubes 35 and such water as does enter these tubes will be drained back through the drainage tubes 43 into the tubes 41. The tubes 41 will be small enough so that they can be made of sufficient strength and yet, by reason of their number and position, will give a reserve water capacity substantially the same as the usual drum for such boilers.

The approximate water level is indicated in Fig. 1, by the line A—A, but it is to be understood that this water line may vary widely under different operating conditions.

It will be noted that in the arrangement illustrated, all of the sections are substantially circular, so that the maximum strength for a given thickness of metal is obtained

and also that the sections are all relatively small for the same purpose. At the same time, the boiler is arranged so as to have the necessary reserve water capacity and so that the steam will be separated from the water 5 and substantially dry steam passed to the main steam pipe.

In the arrangement shown in Fig. 6, the 10 construction is the same as that shown in Fig. 1, except that instead of a single row of tubes 41, as in Fig. 1, there is shown a plurality of rows 41, which can therefore be made of smaller diameter than if only a single row were used, so that the same reserve water capacity can be obtained by the 15 use of smaller diameter tubes. In this figure the approximate water line is also shown, but here again it is to be understood that the line may vary quite widely from that shown.

It will be understood that while the arrangement of headers and tubes shown best 20 in Figs. 4 and 5 are the ones which I preferably use, other forms of water chambers may be used in connection with some of the other 25 features of my invention. It will also be understood that the embodiment of my invention may be widely varied.

I claim:

1. A water tube boiler having inclined water tubes connected at their opposite ends to 30 uptake and downtake water chambers, a plurality of water storage tubes of relatively large cross-sectional area extending between and connected to the upper portion of the uptake and the downtake water chambers 35 and inclined upwardly from the downtake water chamber, a plurality of steam circulating tubes extending between and connected to the uptake and the downtake water chambers above said water storage tubes, 40 a vertically disposed main steam pipe, and a row of auxiliary steam collecting pipes spaced along the upper portion of the downtake water chamber with their upper ends connected to said main steam pipe.

2. A water tube boiler having inclined water tubes connected at their opposite ends to 50 uptake and downtake water chambers, a plurality of water storage tubes of relatively large cross-sectional area extending between and connected to the upper portion of the uptake and the downtake water chambers and inclined upwardly from the downtake water chamber, a plurality of steam circulating tubes connecting the uptake and the 55 downtake water chambers above said water storage tubes, a main steam pipe, a steam equalizing tube extending above the downtake water chamber, nipples spaced across the water 60 chamber and connecting said steam equalizing tube to said downtake water chamber, tubes connecting said steam equalizing tube to said main steam pipe, and drain tubes for 65 said steam equalizing tube to the water spaces of the boiler.

3. A water tube boiler having inclined water tubes connected at their opposite ends to 70 uptake and downtake water chambers, each of said chambers comprising vertically disposed headers, a plurality of water storage tubes of relatively large cross-sectional area extending between and connected to the upper portion of the uptake and the downtake water chambers and inclined upwardly from the 75 downtake water chamber, each of said water storage tubes being nippled to the uptake chamber by a substantially axial nipple and also by one or more curved connectors each having one end connected into the side of said water storage tube and the other end into the uptake water chamber, and a plurality of steam circulating tubes connecting the uptake and the downtake water chambers above said water storage tubes.

4. A water tube boiler having inclined water tubes connected at their opposite ends to 80 uptake and downtake water chambers, a plurality of water storage tubes of relatively large cross-sectional area extending between and connected to the upper portion of the uptake and the downtake water chambers and inclined upwardly from the 85 downtake water chamber, a plurality of steam circulating tubes connecting the uptake and the downtake water chambers above said water storage 90 tubes, and drain tubes extending from said steam circulating tubes downwardly to said water storage tubes.

5. A water tube boiler having inclined water tubes connected at their opposite ends to 95 uptake and downtake water chambers, a roof baffle above the water tubes and spaced therefrom to provide a gas passage space, said water chambers each extending a substantial distance above said roof baffle, water storage tubes of relatively large cross-sectional area above said roof baffle and connected to the uptake and the 100 downtake water chambers, steam circulating tubes above said water storage tubes and connecting the uptake and the 105 downtake water chambers, a main steam pipe and connections between said main steam pipe and the upper end of the 110 downtake water chamber at a plurality of points across the boiler.

6. A water tube boiler having inclined water tubes connected at their opposite ends to 115 uptake and downtake water chambers, a roof baffle above the water tubes and spaced therefrom to provide gas passage space, said water chambers each extending a substantial distance above said roof baffle, water storage tubes of relatively large cross-sectional area above said roof baffle and connected to the uptake and the 120 downtake water chambers, steam circulating tubes above said water storage tubes and connecting the uptake and the 125 downtake water chambers, a vertically disposed steam collecting chamber at a level above that of the tops of the water chambers, 130

- a main steam pipe connected to said chamber and a row of auxiliary steam collecting pipes spaced along the upper portion of the downtake water chambers with their upper ends connected to said chamber.
6. 7. A water tube boiler having inclined water tubes connected at their opposite ends to a plurality of uptake headers and a plurality of downtake headers, a roof baffle above the water tubes and spaced therefrom to provide gas passage space, a row of vertically-extending pipes of relatively large cross-section above said headers with the lower end of each pipe nipped to its respective header, horizontally inclined water storage tubes of relatively large cross-sectional area each extending between and nipped to a pipe in one of said rows and a pipe in another of said rows, a main steam pipe, and auxiliary steam collecting pipes connected between the tops of both of said rows of vertically-extending pipes and said main steam pipe.
8. A water tube boiler having inclined water tubes connected at their opposite ends to a plurality of uptake headers and a plurality of downtake headers, a roof baffle above the water tubes and spaced therefrom to provide gas passage space, a row of vertically-extending pipes of relatively large cross-section above said headers with the lower end of each pipe nipped to its respective header, horizontally inclined water storage tubes of relatively large cross-sectional area each extending between and nipped to a pipe in one of said rows and a pipe in another of said rows, a main steam pipe, and auxiliary steam collecting pipes connected between the tops of both of said rows of vertically-extending pipes and said main steam pipe, each of said 25 horizontally-inclined water storage tubes being also connected to its respective vertically-extending pipe by a plurality of curved connectors each extending from the side of said tube to the side of said pipe.
45. 9. A water tube boiler having inclined water tubes connected at their opposite ends to a plurality of uptake headers and a plurality of downtake headers, a roof baffle above the water tubes and spaced therefrom to provide 50 gas passage space, a row of vertically-extending pipes of relatively large cross-section above said headers with the lower end of each pipe nipped to its respective headers, horizontally inclined water storage tubes of relatively large cross-sectional area each extending between and nipped to a pipe in one of said rows and a pipe in another of said rows, said horizontally inclined pipes being located above said roof baffle, a horizontal box 55 above the upper ends of the row of vertically-extending pipes connected to the downtake water chambers and nipped to each of said pipes, steam circulating tubes each connecting one of said vertically-extending tubes above 60 the uptake water chambers with said horizontal box, a main steam pipe, and a plurality of auxiliary steam collecting pipes leading to said main steam pipe from spaced points along said horizontal box.
10. A water tube boiler having inclined water tubes divided into groups across the boiler, 70 a plurality of uptake headers and a plurality of downtake headers, each connected to one of said groups of tubes, baffling to direct furnace gases transversely of the water tubes, a roof baffle between the uptake and downtake headers and spaced from the water tubes to provide gas passage space, each of said headers having an extension nipped to the upper end of the header and extending above the roof baffle, each extension comprising a pipe circular in cross-section and of relatively large area, a horizontally inclined tube of relatively large area extending above said roof baffle and nipped between an uptake and a downtake extension, a main steam pipe, and auxiliary pipes connected between the tops of 75 said extensions and said main steam pipe.
11. A water tube boiler having vertically disposed water chambers divided into sections, water tubes connecting the water chambers, a steam equalizing tube extending along and above the top of one of the water chambers and above the water level therein, connections between each section of said water chamber and the steam equalizing tube, a vertically disposed steam collecting chamber and tubes spaced along the steam equalizing tube and connected to said steam collecting chamber.
12. A water tube boiler having vertically disposed uptake and downtake water chambers divided into sections, inclined water tubes connecting the water chambers, a steam equalizing tube extending along and above the top of said downtake water chamber and above the water level in the boiler, connections between each section of said downtake water chamber and the steam equalizing tube, a vertically disposed steam collecting chamber, 100 and tubes spaced along the steam equalizing tube and connected to said steam collecting chamber.
13. A water tube boiler having inclined water tubes connected at their opposite ends to uptake and downtake water chambers, said chambers being divided into vertically disposed sections, a steam equalizing tube extending along and above said downtake water chamber and above the water level of the boiler, a vertically disposed steam collecting chamber, a row of pipes each connected to said equalizing tube and said downtake water chamber and in vertical alinement with a section thereof, a row of pipes connecting said equalizing tube and said steam collecting chamber, the ends of each pipe in each of said rows being in alinement with the ends of a pipe in the other of said rows.
14. A water tube boiler having inclined wa- 130

ter tubes connected at their opposite ends to uptake and downtake water chambers, said chambers being divided into vertically disposed sections, a box extending along and above the top of the downtake water chamber, a steam equalizing tube extending along and above said box and above the water level of the boiler, a vertically disposed steam chamber; a first row of tubes, each connecting a section of the downtake water chamber with said box, a second row of tubes connecting said box and said equalizing tube and a third row of tubes connecting said equalizing tube and said steam chamber, the ends of each pipe in each row being substantially in alinement with the ends of a pipe in each of the other rows.
